CLAIM

The ornamental design for tee cube connector for wall panel system, as shown and described.

DESCRIPTION

FIG. 1 is a perspective view of a first embodiment of a tee cube connector for a wall panel system, showing our new design.

FIG. 2 is another perspective view thereof.

FIG. 3 is a front elevation view thereof.

FIG. 4 is a rear elevation view thereof.

FIG. 5 is a top plan view thereof.

FIG. 6 is a bottom plan view thereof.

FIG. 7 is a right side elevation view thereof.

FIG. 8 is a left side elevation view thereof.

(Continued)

FIG. 9 is a perspective view of a second embodiment of a tee cube connector for a wall panel system.

FIG. 10 is another perspective view thereof.

FIG. 11 is a front elevation view thereof.

FIG. 12 is a rear elevation view thereof.

FIG. 13 is a top plan view thereof.

FIG. 14 is a bottom plan view thereof.

FIG. 15 is a right side elevation view thereof; and,

FIG. 16 is a left side elevation view thereof.
